UNITED STATES PATENT OFFICE

SIMEON E. TRAVIS, JR., OF HATTIESBURG, MISSISSIPPI

CARRIER OF THE PLURAL-DECK TYPE

Application filed January 6, 1930. Serial No. 418,851.

This invention relates to a carrier of the plural deck type designed primarily for receiving boxed or cased bottled goods for transportation purposes, but it is to be understood that a carrier, in accordance with this invention may be employed for the transporting of any character of goods for which it is found applicable, and the invention has for its object to provide, in a manner as hereinabove set forth, a plural deck carrier for use in connection with a motorcycle of the side car type, in lieu of the side car body of the latter to provide for the quick transportation of a large quantity of goods, as well as permitting the expeditious positioning of the goods into and their removal from the carrier when occasion requires.

A further object of the invention is to provide, in a manner as hereinafter set forth, a plural deck carrier for the purpose referred to including a pair of opposed corner rails extended a substantial distance from the upper deck of the carrier for the purpose of suspending a sign in an elevated position with respect to the upper deck of the carrier body.

Further objects of the invention are to provide, in a manner as hereinafter set forth, a plural deck carrier for the purpose referred to which is simple in its construction and arrangement, strong, durable, compact, of skeleton form, readily assembled, thoroughly efficient when used, quickly installed with respect to a motorcycle, and inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a side elevation, partly in section of a carrier in accordance with this in-

vention, showing the adaptation thereof with a motorcycle of the side car type.

Figure 2 is a view looking toward the rear end of the carrier and with the sign in vertical section.

Figure 3 is a section on line 3—3, Figure 1.

Figure 4 is a fragmentary view in perspective illustrating a portion of the lower deck of the carrier.

Figure 5 is a fragmentary view in side elevation illustrating a portion of the lower deck of the carrier and which is modified with respect to the showing of the lower deck in Figure 4.

Figure 6 is an end view, broken away, of a modified form of carrier.

The drawing illustrates one of the wheels of a side car structure for a motorcycle and such wheel is indicated at 1 and is carried by the rear axle 2. The side car structure includes a front and a rear stirrup indicated at 3, 4 respectively. The stirrup 3 is connected, at its ends, as at 6 to one end and stirrup 4 is connected at its ends, as at 7 to the other end of the side springs 5 of the side car structure. As shown the side springs 5 are coupled with the axle 2. The connection 6 between the side springs 5 and the stirrup 3 is forwardly of the axle 2 and the connection 7 between the side springs 5 and the stirrup 4 is rearwardly of the axle 2.

Referring to Figures 1 to 4 of the drawings, the carrier includes a pair of lower side rails 8, 9 and a pair of lower end rails 10, 11. The carrier also includes a pair of upper side rails 12, 13 and a pair of upper end rails 14, 15. Each side and end rail is of angle-shaped cross section and includes a vertically disposed leg and an inwardly extending, horizontally disposed leg which projects from the bottom of the vertical leg. The upper side and end rails are arranged a substantial distance above the lower side and end rails.

The end rails 10 and 11 are arranged between and connected to the ends of the side rails 8, 9. The end rails 14 and 15 are arranged between and connected to the ends of the side rails 12, 13. The ends of the side rails are connected to the ends of the end

rails in a manner whereby the vertical portions of such rails will be flush with each other. The side and end rails are connected in a manner whereby the horizontal portions of the side rails will abut and be welded to the horizontal portions of the end rails.

The carrier also includes two pairs of corner rails. The corner rails of one pair are indicated at 16, 17 and the corner rails of the other pair at 18, 19. Each of the corner rails is of angle-shape in cross section to provide a pair of legs 20, 21 disposed at right angles with respect to each other and with the leg 21 projecting outwardly from the inner side edge of leg 20. The rails 16, 17 are of a length materially greater than the length of the rails 18, 19.

The legs 20 of the rails 16, 17 are welded to the outer faces of the vertical legs of the rails 8, 12. The legs 20 of the rails 16, 17 have their outer side edges flush with the outer faces of the vertical legs of the upper and lower end rails. The legs 21 of the rails 16, 17 project outwardly at right angles with respect to the vertical legs of the rails 8, 12.

The legs 20 of the rails 18, 19 are welded to the outer faces of the side rails 9, 13. The outer edges of the legs 21 are flush with the outer faces of the vertical legs of the end rails. The lower ends of the rails 16, 17 are flush with the horizontal legs of the rails 8, 9, 10 and 11. The upper ends of the rails 16, 17 extend a substantial distance above the rails 12, 13, 14 and 15. The lower ends of the rails 18 and 19 are flush with the horizontal legs of the rails 8, 9, 10 and 11. The upper ends of the rails 18, 19 are flush with the top edges of the vertical legs of the rails 12, 13, 14 and 15. The corner legs 16, 17, 18 and 19 are welded to the side rails 8, 9, 12 and 13 at adjacent points to maintain the legs 12, 13 in superposed spaced relation with respect to the legs 8, 9.

Secured upon the horizontal legs of the rails 8, 9, 10 and 11 is a corrugated flooring 22 which extends from the vertical leg of the rail 8 to the vertical leg of the rail 9 and from the vertical leg of the rail 10 to the vertical leg of the rail 11.

Secured upon the horizontal portions of the rails 12, 13, 14 and 15 is a corrugated flooring 23 and which extends from the vertical leg of the rail 12 to the vertical leg of the rail 13 and from the vertical leg of the rail 14 to the vertical leg of the rail 15.

The rails 8, 9, 10 and 11 in connection with the flooring 22 provide the lower deck and the rails 12, 13, 14 and 15 in connection with the flooring 23 provide the upper deck of the carrier. The vertical leg of the rail 8 and the vertical leg of the rail 9 at points between the center of such leg and each end thereof are cut out, as indicated at 24 in Figure 4 to provide clearances. Secured to the vertical leg of each lower side rail and registering

with each cut out in such leg is an upstanding, vertically disposed, inverted, yoke-shaped reinforcing member 25 provided at its top with an opening 26. The inner edges of the arms of each member 25 register with the vertical edges of the cutouts 24. The cutouts 24 provide clearances for the vertical arms of the stirrups 3, 4 and the stirrups, as shown in Figures 2 and 3, are connected to the top of the members 25, as at 27.

Seated on each top and arranged between the horizontal legs of the members 8, 9 is a filler strip 28. The arrangement of filler strip is shown in Figure 3. The flooring 22 seats on filler strip 28.

Figure 5 illustrates a modified form of inverted, yoke-shaped member which is employed for reinforcing the vertical legs of the side rails 8, 9 at the cutout portions thereof. In Figure 5 the inverted, yoke-shaped member is indicated at 29 and is integral with the vertical legs of the side walls. The member 29 is of less height than the member 25 and is employed when the connections for the side springs of the motorcycle are not as high as that shown in Figure 3 and also of different form, that is to say, the connections between the side springs of the motorcycle and the stirrups.

In Figure 4, the member 25 is not a continuation of the vertical legs of the lower side members but is formed of separate pieces of material welded together in inverted, yoke-like form and also welded to the vertical legs of the lower side rails.

The form shown in Figure 6 is the same as that shown in Figures 1, 2 and 3, with this exception that the corner rails are formed flat and not of angle-shaped cross section. In Figure 6 the shorter corner rails are indicated at 30 and the longer corner rails at 31.

A sign board or frame shown in Figure 1 and indicated at 32 is arranged between, welded to the upper ends of the legs 21 of the side rails 16, 17 and suspended in a superposed, spaced relation with respect to the carrier at one side thereof.

In Figure 6 a sign board or frame indicated at 33 has its ends welded centrally thereof to the inner edges of the corner rails 31. In Figure 6 the corner rails 30, 31 have their inner side faces welded to the outer faces of the vertical legs of the upper and lower side rails of the body of the carrier. The corner rails 30 are flush at their upper ends with the top edges of the vertical legs of the upper rails and at their lower ends flush with the horizontal legs of the lower rails. The corner rails 31 have their lower ends flush with the horizontal legs of the lower rails and extend a substantial distance above the upper rails for the purpose of suspending the sign or sign frame in superposed, spaced relation with respect to the carrier and at one side thereof.

What I claim is:—

1. In combination, a side car structure for a motorcycle including a pair of spaced, opposed stirrups disposed at right angles to the line of travel of the cycle and resilient supporting means for the stirrups, a plural deck carrier supported by, connected with and extending above the said stirrups and including a bottom, and filler members between the bottom of the carrier and said stirrups.

2. In combination, a side car structure for a motorcycle including a pair of spaced, opposed stirrups disposed at right angles to the line of travel of the cycle and resilient supporting means for the stirrups, a plural deck carrier supported by, connected with and extending above the said stirrups and including a bottom, and filler members disposed transversely of the bottom of the carrier, interposed between said bottom and the upper face of said stirrups and further abutting the bottom and said stirrups.

3. A carrier comprising a body formed of an upper and a lower deck each including a pair of end and a pair of side rails and a bottom surrounded by and secured to said rails, each of said rails including a horizontal leg and a vertical leg extending upwardly from the outer side of the vertical leg, said vertical legs projecting above said bottom, corner rails secured to said side rails for maintaining said decks in spaced relation, and the vertical legs of the side rails of the lower deck having spaced cutouts to provide for the mounting of the carrier upon supporting stirrups carried by a motorcycle, and reinforcing means for the vertical legs of the side rails bordering said cutouts.

4. A carrier for use on motorcycles of the side car type comprising a pair of decks, and two pair of corner rails secured to said decks for maintaining them in superposed spaced relation, the lower of said decks having each side provided with spaced cutouts to form clearances for supporting stirrups for the carrier, said lower deck provided with reinforcements at said cutouts.

5. A carrier for use on motorcycles of the side car type comprising a body open at its sides and including a plurality of decks and upstanding, angle-shaped rails for connecting said decks together in superposed spaced relation, each of said rails including a leg secured to said decks and a leg extending at right angles to the deck, certain of said rails extending above the upper of said decks and adapted to have the angularly disposed legs thereof support a sign above and at one side of the upper deck.

6. A carrier for use on motorcycles of the side car type comprising a body open at its sides and ends and including a plurality of decks and upstanding, spaced rails for connecting said decks in superposed, spaced relation, each of said decks including a pair of end and a pair of side rails and a bottom, said rails of each deck having inwardly extending portions at the lower part thereof for supporting the bottom of the deck, and the side rails of the lower deck having spaced cutouts to provide clearances for supporting stirrups for said lower deck.

7. A carrier for use on motorcycles of the side car type comprising a body open at its sides and ends and including a plurality of decks and upstanding, spaced rails for connecting said decks in superposed, spaced relation, each of said decks including a pair of end and a pair of side rails and a bottom, said rails of each deck having inwardly extending portions at the lower part thereof for supporting the bottom of the deck, the side rails of the lower deck having spaced cutouts to provide clearances for supporting stirrups for said lower deck.

8. A carrier for use on motorcycles of the side car type comprising a body open at its sides and ends and including a plurality of decks and upstanding spaced rails for connecting said decks in superposed spaced relation, each of said decks including a pair of end and a pair of side rails and a bottom, said rails of each deck having inwardly extending portions at the lower part thereof for supporting the bottom of the deck, the side rails of the lower deck having spaced cutouts to provide clearances for supporting stirrups for said lower deck, and filler means between the bottom of said lower deck and the stirrups.

9. A carrier for use on motorcycles of the side car type comprising a body open at its sides and ends and including a plurality of decks and upstanding spaced rails for connecting said decks in superposed spaced relation, each of said decks including a pair of end and a pair of side rails and a bottom, said rails of each deck having inwardly extending portions at the lower part thereof for supporting the bottom of the deck, the side rails of the lower deck having spaced cutouts to provide clearances for supporting stirrups for said lower deck, and reinforcing means for the lower deck bordering said cutouts.

In testimony whereof, I affix my signature hereto.
